UNITED STATES PATENT OFFICE.

CHARLES H. HARD, OF ONEIDA, NEW YORK.

COT-BED.

SPECIFICATION forming part of Letters Patent No. 252,459, dated January 17, 1882.

Application filed December 13, 1881. (Model.)

To all whom it may concern:

Be it known that I, CHARLES H. HARD, of Oneida, in the county of Madison and State of New York, have invented certain new and useful Improvements in Cot-Beds; and I do hereby declare that the following is a full, clear, and exact description thereof, reference being had to the accompanying drawings, and to the letters of reference marked thereon, which 10 form part of this specification, in which—

Figure 1 is a bottom perspective view of my cot. Fig. 2 is a view of the same when folded. Fig. 3 is a vertical longitudinal section; Fig. 4, an enlarged side view of the head-rest, and 15 Fig. 5 an enlarged perspective of the side bar with the leg-brace connections.

My invention relates to cots wherein a piece of canvas is secured to a folding frame, and wherein the legs and head rest can also be folded, so as to reduce the cot to a very compact 20 shape for facility of packing and transportation.

The improvements which I have made on folding cots consist mainly in the combination, 25 with two side bars, to which the canvas bottom is attached, of jointed or folding legs, crossed or extension lever braces for the legs, and braces which are pivoted at their lower ends to the legs and provided with angular upper ends 30 which slide in stop slots, and are held therein by suitable guards, as will be hereinafter explained.

My invention also consists in the combination of longitudinally-folding supporting and 35 stretching bars with a flexible head-rest, as will be hereinafter explained.

The letter A designates the bottom of the bed or cot, which is usually made of strong canvas, and which in the present instance is secured to two parallel side bars, B B, of suitable 40 width to afford the required rigidity.

B' B' B' B' designate four supporting-legs, which are pivoted to the inner sides of the side bars, B, so as to fold toward the middle of the 45 length thereof and lie closely between them, as shown in Fig. 2. To eyes a, which are fixed to the inner sides of the legs, are linked, by similar eyes, b, crossed braces C C, which are pivoted together in pairs at the middle of their 50 length, and jointed by eyes c to eye-posts d, rigidly fixed to the inner sides of the side bars,

B, near the extremities thereof. The two pairs of braces C C operate in the manner of extension-levers, and collapse and extend laterally while expanding or contracting the cot. When 55 the cot is fully contracted the said braces lie one over the other in pairs, and as the eyes and eye-posts above described are also arranged so as to lie over each other in pairs, it will be seen that the width of the cot when contracted 60 will only be equal to the thickness of the two side bars, two legs, and one of the extension levers or braces. The braces C serve, as their name implies, to brace the legs B' when extended against lateral thrust or strain. They 65 connect the legs of one side bar to the opposite side bar, and they do not interfere with the collapsing of the cot or the distension thereof, nor with the folding or extension of the legs.

To each one of the legs B' is pivoted a brace, 70 D, which is bent as shown in the drawings. The free end of each brace is turned outward, and enters a groove, c', made longitudinally into the inner side of the side bar, and is held therein by a guard-rail, d'. The outer end of 75 each groove c' terminates in a short right-angular extension, c'', which is designed to receive the angular free end of the brace D when the side bars, B, are fully extended, to lock the parts in this position.

To erect the cot the legs are adjusted in the inclined positions shown in Fig. 1, and the angular ends of the braces D are pressed downward into the short slots c''. To fold the cot the said angular ends of the braces D are adjusted into the longitudinal slots c' and the side bars are pressed together, which will bring the legs and their braces snugly between said bars.

G G designate the supporting-bars for the 90 flexible head-rest J. Each bar G is pivoted to two arms, h h', that are pivoted in semicircular recesses f, formed on the upper outer edge of the side bars, B B. These arms h h' are near their lower ends bent at right angles, as seen 95 at e, Fig. 4, thus enabling them to lie along the top of the rail B when folded down, and forming a shoulder which abuts against the edge of the recess f when the head-rest is raised and prevents it from falling backward.

What I claim as new, and desire to secure 100 by Letters Patent, is—

1. The combination of the folding side bars, the flexible bottom secured thereto, the pivoted legs, and the extension or crossed braces pivoted together and connected by linked eyes to said legs and side bars, substantially as described.
2. The combination of the side bars having a flexible bottom secured to them, the folding legs pivoted to the side-bars, the extension-
10 braces pivoted to the side bars and legs, the angular pivoted braces D, the grooves $c' c''$, and the guard-rails d' , substantially as described.
3. The combination of the flexible head-rest J, the folding and supporting bars G therefor, the angularly-bent arms $h h'$, and the recesses f therefor, substantially as described. 15

In testimony that I claim the foregoing as my own I affix my signature in presence of two witnesses.

CHARLES H. HARD.
